UNITED STATES PATENT OFFICE.

WALTER G. BURNS, OF FORT WAYNE, INDIANA.

DRIVING MECHANISM FOR ORE-CONCENTRATORS.

1,858,451.

Specification of Letters Patent. Patented Sept. 21, 1920.

Application filed September 26, 1919. Serial No. 326,593.

To all whom it may concern:

Be it known that I, WALTER G. BURNS, a citizen of the United States of America, and resident of Fort Wayne, in the county of Allen and State of Indiana, have invented certain new and useful Improvements in Driving Mechanism for Ore-Concentrators, of which the following is a specification.

10 This invention relates to improvements in driving mechanism for ore concentrators of that class used for imparting differential reciprocations to a table upon which mineral is separated from its ore, and the objects thereof are: First, to so construct the apparatus as to admit of adjustments that effect various degrees of differential action in the reciprocal movements imparted to the table, and so that the adjustments may be 15 readily made while the apparatus is in operation; second, to construct the apparatus so that its period of maximum differential action may be adjustably shifted while in operation from one point to another in its 20 cycle of movement; third, to construct the apparatus so that the adjusting members for its differential action and the drive-wheel may be transposed from one side of the machine to the other; and fourth, to 25 provide a housing for supporting and containing the principal working parts of the apparatus, so constructed as to hold a quantity of lubricating oil for automatically 30 bathing the working parts and to circum- 35 vent seepage of the oil from between the parts of the housing.

The objects of the invention are accomplished by the construction illustrated in the accompanying drawings in which;—

40 Figure 1 is an end elevation of the driving mechanism;

Fig. 2 is a detail view showing the end of the eccentric shaft opposite that shown in Fig. 1 including a portion of the main stand partly broken away and in section, 45 and the securing means for the shaft;

Fig. 3 is a detail view of the adjustable eccentric and the drag ring mounted thereon and including the drive-shaft, parts 50 thereof being broken away and in section;

Fig. 4 is an elevation of the device in a position opposite that of Fig. 1 and including part of a table with connecting parts, the main stand being in central section and 55 other parts being broken away and in section;

Fig. 5 is a rear elevation of Fig. 4, the main stand being partly in longitudinal central section;

Fig. 6 is a plan view of the device, a portion thereof being broken away;

Fig. 7 is a detail view showing a partial bottom plan of the cover for the main stand; and

Fig. 8 is a detail end view showing an assemblage of the follower, drive-crank, drag-ring mounted upon its eccentric bearing, the toggles, and the drive-shaft, the latter being shown in cross-section and other movable parts being shown in dotted outline in opposite positions.

Similar characters of reference indicate corresponding parts throughout the several views, and having reference now to the same;

1 is the main stand, the ends 2 of which are counterparts oppositely arranged in parallel relationship, and each has a supporting boss 3 for the eccentric shaft 4 and is cast integral with a trough 5 which is transversely disposed. At each end of the trough is a chambered saddle 6 with a duct 7 made therein extending from the bottom of its chamber 8 into the trough. In the upper edges of the trough, extending along the front, back and ends thereof, and across the adjacent parts of the saddles into the chambers 8 thereof, are corresponding continuous grooves 9, the external lips 10 along the grooves projecting higher than the internal lips 11 so that any excess of oil that may be splashed from the trough into the grooves will overflow directly back into the trough or pass indirectly back thereinto through the chambers 8 and ducts 7.

A cover 12 is positioned over the trough and has at each end thereof a chambered cap 13 that rests upon the corresponding saddle 6 on the main stand, and has also at its front, back and ends, continuous beads 14 that depend respectively into the adjacent grooves 9 in the trough, the arrangement of which serves as an oil trap that tends to prevent escape of the contained oil out from between the cover and trough. Overhanging ledges 15 along the lower edges of the cover extend over the corresponding external lips 10 on the stand, there being grooves 16 up into which the respective lips project. The grooves 16 also extend across the adjacent faces of the caps 13 into the chambers 17 therein respectively. The ledges prevent

trance of foreign matter into the grooves in the trough, and the grooves extending across the faces of the saddles and caps divert oil from between the faces into the chambers 8 and 17. The lips 10 and 11 on the trough and the grooves 9, and the ledges 15, bead 14 and grooves 16 of the cover 12 are so proportioned and positioned that an open space 18 is left between each edge of 10 the cover and corresponding edge of the trough when the caps rest in place respectively upon the saddles. Thus, creeping of oil by capillary attraction out from between the cover and trough is obviated. In the 15 top of the cover is a hand-hole 19 which is closed by a lid 20, and in the front of the cover is made a hood 21 through the opening 22 of which extends an arm 23 of a bell-crank 24, the latter being mounted loosely 20 upon the eccentric 25 of the shaft 4. The hood 21 has an internal bead 26 at its front and the arm 23 of the bell-crank has a projecting guard 27 which prevents oil from splashing out through the hood opening.

25 The ends of the eccentric shaft 4 extend into corresponding split bushings 28 that are positioned respectively in the supporting bosses 3, each bushing being held therein by a cap-screw 29 in position to be clamped 30 upon the shaft 4 by a set-screw 30, and hold the shaft in adjusted positions. One end of the shaft projects outwardly and has fixed thereon an adjusting nut 31 having an integral lug 32 that limits the turning movement 35 of the eccentric shaft by coming into contact with either end of a segmental flange 33 on the boss. The nut has also an index 34 positioned oppositely from the eccentric so that the adjusted positions thereof 40 may be determined.

The bell-crank 24 has a slotted pendent arm 35 in which is arranged a cross-head 36, and a screw 37 extending therethrough for the vertical adjustment of the cross-head. A handpiece 38 is fixed upon the upper end of the screw by which it is turned. A yoke-pin 39 in the cross-head has connection with a yoke 40 and the latter is coupled with a swinging lever 41 by 45 an eye-bolt 42 and pin 43. The base 44, reciprocating table 45 and the swinging lever 41 are of a character well known, the table being held constantly against the swinging end of the lever by the pressure of a spring 50 55 (not shown), so that the table is moved in one direction by the action of the spring and in the opposite direction by the reverse action of the lever. Thus, as the bell-crank rocks upon the eccentric 25 the table is reciprocated.

Between each saddle 6 and corresponding cap 13 is positioned a journal box 46 and 47 respectively which support the drive-shaft 48 in central alinement in the housing 65 formed by the trough and cover. One end

of the drive-shaft projects outwardly and has mounted thereon a drive-wheel 49 and loose pulley 50. The journal box 46 has near its outer end an internal annular recess 51 and a duct 52 leading therefrom 70 into the chamber 8 of the saddle 6 for the passage of surplus oil from the journal box thereinto, and a ring 53 fitting tightly upon the shaft 48 and extending into the recess 51 prevents oil from escaping from the end 75 of the journal box. The inner end of the journal box 46 has a chaffing flange 54, and also a slot 55 in which extends a ring oiler 56 for the shaft 48. The outer end 57 of the journal box 47 is hexagonal and adapted 80 for the application of a wrench for adjustably turning it in the saddle in which the box is held. The inner end of the journal box 47 has an integral eccentric 58 upon which is loosely mounted a drag-ring 59 85 having two pins 60 each of which projects in a line parallel with the drive-shaft 48. The drag-ring has oil-holes 61 through which the eccentric is lubricated, and the eccentric also has an oil-hole 62 through which the 90 drive-shaft receives lubricant from between the drag-ring and eccentric.

Upon the drive-shaft is fixed a drive-crank 63 having a wrist-pin 64 which is linked with one of the pins 60 on the drag-ring by a toggle 65, so that as the crank revolves with the shaft the drag-ring is rotated upon the eccentric 58. Upon the drive-shaft is loosely mounted a follower consisting of an oscillating eccentric 66 having a radially disposed integral arm 67 at one end thereof provided with a wrist-pin 68 positioned to move in the same path as the wrist-pin 64 on the drive-crank. The other pin 60 on the drag-ring is coupled 100 with the wrist-pin 68 on the arm 67 by a toggle 69 so that as the drag-ring rotates upon the eccentric 58 the follower is caused to revolve with the drive-shaft as its axis. The pins 60 on the drag-ring are directed 105 thereby in a circular path that is eccentric to the drive-shaft, and the wrist-pin 64 and 68 on the drive-crank 63 and radial arm 67 respectively travel in a circular path that is concentric with the drive-shaft, and consequently during each cycle of movement the toggles function as such, causing the radial arm and the eccentric 66 integral therewith to oscillate upon the drive-shaft. Thus, when the drive-shaft is rotated uniformly, the eccentric 66 is rotated differentially. By turning the journal box 47 the eccentric bearing 58 integral therewith may be adjustably positioned so that the period of maximum differential action in the cycle 110 of movement of the oscillating eccentric will accordingly be changed. The journal box 47 is held in adjusted positions by tightening the bolts 13'. The drive-crank 63 and the radial arm 67 each have a beater 115 120 125 70 130

projecting from its outer end adapted to splash oil from the body 71 contained in the trough onto the adjacent working parts of the mechanism as they revolve.

5. A roller 72 is loosely mounted upon the oscillating eccentric 66 and is held thereon between the radial arm 67 and the chaffing flange 54 at the inner end of the journal box 46, and upon the roller rests the curved bearing 73 of the arm 23. As the oscillating eccentric revolves with the drive-shaft and oscillates thereon, the roller thereby is gyrated differentially and rolls back and forth in constant contact with the curved bearing 73, which action augments the differential rocking movement imparted to the bell-crank. By adjustably turning the eccentric shaft 4 the bell-crank may be shifted so that the augmented differential action thereof will be more or less pronounced accordingly.

The oscillating eccentric 66 has an internal oil groove 74 extending longitudinally therein through which it receives surplus lubricant from the journal box 46 adjacent thereto, and has also an oil passageway 75 through which the roller receives oil from the groove 74, there being a longitudinal groove 76 for distributing the lubricant between the oscillating eccentric and the roller mounted thereon. Thus, as the drive-shaft rotates, the ring oiler 56 deposits oil from the body contained in the trough and into which the ring oiler depends onto the drive-shaft, effecting lubrication of the journal box 46 and the operating parts of the mechanism adjacent thereto.

In operating the invention, the drive-shaft together with all of the parts mounted thereon including the journal boxes may be 40 placed in the housing in the reverse position if so desired, in which event the respective connections between the drive-crank and radial arm and their toggles should be transposed, and the eccentric shaft 4 should also be reversed endwise so that the adjusting nut 31 will be conveniently accessible from the side of the machine opposite the drive-wheel. The body of lubricating oil is maintained in the trough by occasional replenishment through the hand-hole in the cover, and the drive-wheel is rotated uniformly over toward the table by applying a belt in the customary manner. The oil in the trough is splashed about therein over the 50 contained working parts by the action of the beaters, and the grooves 9 in the edges of the trough become filled to the extent that the lower edges of the beads 14 are submerged, thus the oil-charged atmosphere 55 that is circulated by the rotating mechanism is retained within the housing. Any overplus of oil that may enter the grooves either overflows the internal lips 11 or flows into the chambers 8 and returns into the trough 60 through the ducts 7.

The length of stroke imparted to the table may be varied by manipulating the adjusting screw 37; the velocity ratio between the forward and return strokes may be altered by adjustably positioning the eccentric 58; 70 and the differential character of the cycle of movements may be accentuated more or less by adjustably turning the eccentric shaft 4.

What I claim is:—

1. In mechanism of the class described 75 having a main stand and rocking member, a drive-shaft; a drive-crank fixed thereon; a bearing eccentrically positioned relative to the drive-shaft; a drag-ring on the bearing; an eccentric having a radial arm, 80 loosely mounted on the drive-shaft; a pair of toggles carried by the drag-ring, having connections respectively with the drive-crank and radial arm and being adapted to impart oscillating movement to the eccentric as it 85 is revolved; and a roller on the eccentric for actuating the rocking member.

2. As a new mechanical movement, a rotating driving-member, a revolving drag-member positioned eccentrically thereto, an 90 oscillating follower on the driving member, and a pair of toggles carried by the drag-member and having connections respectively with driving member and follower.

3. As a new mechanical movement, a rotary driving member, a follower loosely mounted thereon, and an eccentrically supported toggle mechanism arranged to be rotated by the driving member and differentially revolve the follower. 95

4. In mechanism including a stand and rocking member, a rotary driving member; a follower loosely mounted thereon; a bearing eccentrically positioned relative to the axis of the driving member; a toggle mechanism rotatable on the bearing, having connections respectively with the driving member and follower and being adapted to be driven by the former and differentially actuate the latter; and a medium on the follower for actuating the rocking member. 105

5. As a new mechanical movement, a rotary driving member; a revolving drag-member; a follower loosely mounted on the driving member; a pair of toggles carried 115 by the drag-member and having connections respectively with the drive member and follower and being adapted to actuate the latter differentially as the former moves uniformly; and a bearing for the drag-member positioned eccentrically relative to the driving member and being adapted to be adjustably turned so as to shift the period of maximum differential action thereof from one part of its cycle to another. 120

6. In mechanism for actuating a rocking member, a drive-shaft having a crank fixed thereon; a drag-member; an eccentric loosely mounted upon the drive-shaft and having a fixed radial arm; a pair of toggles 130

carried by the drag-member and having connections respectively with the crank and arm, and being adapted to impart differential rotary motion to the eccentric 5 when the drive-shaft is revolved uniformly; a bearing for the drag member positioned eccentrically relative to the drive-shaft and being adapted to be adjustably turned so as to shift the period of maximum differential 10 action in the cycle of the eccentric; and an actuating medium between the eccentric and rocking member.

7. In apparatus of the class described, a stand; a mechanism having a differentially

gyrated follower; a rocking member having 15 a curved bearing actuated by the follower; and an adjustable shaft having an eccentric supporting the rocking member; and means in connection with the shaft and stand for adjustably positioning and securing the 20 shaf.

In testimony whereof I affix my signature, in presence of two witnesses.
